FIG. 1 is an isometric view of a shop desk with hutch, with the hutch in an upright reversed orientation on an underside of the shop desk.

FIG. 2 is an isometric view of the shop desk with hutch of FIG. 1, that is horizontally rotated 90° from the angle of the shop desk with hutch shown in FIG. 1.

FIG. 3 is a front view of the shop desk with hutch of FIGS. 1 and 2.

FIG. 4 is a top plan view of the shop desk with hutch of FIGS. 1 and 2.

FIG. 5 is a right side view of the shop desk with hutch of FIGS. 1 and 2 that is symmetric to the left side view thereof.

FIG. 6 is a rear view of the shop desk with hutch of FIGS. 1 and 2; and,

FIG. 7 is a bottom plan view of the shop desk with hutch of FIGS. 1 and 2.

The broken lines form no part of the claimed design.
